(57) **CLAIM**

The ornamental design of a door locking handle for an electrical apparatus box, as shown and described.

DESCRIPTION

FIG. 1 is a left side view of the door locking handle for an electrical apparatus box showing my new design;
FIG. 2 is a front elevational view thereof;
FIG. 3 is a right side elevational view thereof;
FIG. 4 is a rear elevational view thereof;
FIG. 5 is a top plan view thereof,
FIG. 6 is a bottom plan view thereof; and,
FIG. 7 is a cross-sectional view taken at 7—7 of FIG. 2.
